(Cl. D58—26)

Fig. 1 is a perspective view of a container for dental drill packets or the like in open position embodying my new design;

Fig. 2 is a side elevational view, on a reduced scale, showing the container with the transparent cover removed; and

Fig. 3 is a front elevational view of the container of Fig. 2.

The dental drill packets and cover for one of the packets are shown in dotted lines for illustrative purposes only.

I claim:

The ornamental design for a container for dental drill packets or the like, as shown and described.
